(57) **CLAIM**

The ornamental design for a double buckle for a scuba harness, as shown and described.

DESCRIPTION

FIG. 1 is a front perspective view of a double buckle for a scuba harness embodying my new design attached to a scuba harness system, wherein a belt attached to the buckle is shown in broken lines for illustrative purposes only and forms no part of the claimed design;

FIG. 2 is a front view thereof;

FIG. 3 is a bottom view thereof;

FIG. 4 is a left side view thereof;

FIG. 5 is a rear view thereof;

FIG. 6 is a right side view thereof; and,

FIG. 7 is a top view thereof.
